NAPKIN HOLDER

John W. Kennedy, 1285 Baywood Ave.,
South San Francisco, Calif.

Filed May 17, 1965, Ser. No. 85,306

Term of patent 14 years

(Cl. D44—24)

FIG. 1 is an isometric view of a napkin holder, showing my new design, with the follower raised to accommodate a stack of napkins;

FIG. 2 is a front elevational view; and

FIG. 3 is an elevational view taken from the right of FIG. 1.

I claim:

The ornamental design for a napkin holder, substantially as shown.
